UNITED STATES PATENT OFFICE.

JOHN J. RADEL, OF NEWARK, NEW JERSEY.

TELEPHONE INSTRUMENT.

Application filed August 20, 1925. Serial No. 51,385.

This invention relates, generally, to improvements in telephones; and, the present invention has reference, more particularly, to a novel receiver element for telephones, 5 the relation of the said receiver element to the standard or post of the telephone being such, that a pivotal arrangement of the receiver element in one position will interrupt the electrical current used with the telephone, but when in another position, in other words, the receiving position, will complete the electric circuit, and at the same time said receiver element is maintained in its raised or hearing position at the ear or ears of the 10 person at the instrument, without the necessity of the person having to hold the sound-receiving element in place before the ear.

The invention, therefore, has for its principal object, to provide the standard or post 20 of a telephone, and the circuit-making and interrupting means thereof, with a movable or pivoted frame or device, carrying receiving means, which when raised will establish the usual electrical circuit, and when in its 25 fully raised position will remain in such position without any further effort and holding of the device on the part of the user of the telephone, so that the person at the desk has the free use of both hands for other purposes, and still, without any inconvenience, 30 being able to use the telephone for the usual talking and hearing purposes.

Other objects of the present invention not at this time more particularly enumerated 35 will be more fully understood from the following detailed description of the present invention.

With the various objects of the invention in view, the invention consists, primarily, 40 in the novel telephone-instrument herein-after more fully set forth; and, the invention consists, furthermore, in the novel arrangements and combinations of the various devices and parts, as well as in the details of 45 the construction of the said parts, all of which will be more fully described in the following specification, and then finally embodied in the clauses of the claims, which are appended to and which form an essential 50 part of the said specification.

The invention is illustrated in the accompanying drawings, in which:—

Figure 1 is a side-elevation of a telephone-

instrument provided with a self-sustaining sound-receiving element made according to 55 and showing one embodiment of the principles of the present invention; Figure 2 is a front view of the same; Figure 3 is a view showing partly in plan and partly in horizontal section, portions of the frame-members and their pivotal connection with the standard or post of the telephone of the said sound-receiving element; and Figures 4, 5, 60 6 and 7 are detail views of certain members of the pivotal connection of the device. 65

Figure 8 is a view, similar to Figure 1, showing a slight modification of the invention; and Figure 9 is a perspective view, illustrating a fragmentary portion of the standard or post of a telephone-instrument, 70 and showing in connection therewith, a circuit-making and breaking means used with the arrangement of devices as illustrated in said Figure 8.

Similar characters of reference are employed in the said above described views, 75 to indicate corresponding parts.

Referring now to the several figures of the drawings, the reference-character 1 indicates a usual form of telephone-standard or post 80 which is hollow or tubular, and which contains the usual electrical means used with telephones. In its side, the said standard or post has an opening, as 2, in which is movably disposed an oscillatory and spring-controlled, or other suitably actuated make and break-establishing element 3, as indicated in Figures 1 and 2 of the drawings, on which may be a vertically slidably element, as 4, as indicated in Figures 8 and 9. The upper 85 end-portion of the standard or post 1 is bifurcated, as at 5 and 6, between which is pivotally arranged, in a manner to be presently described, a rearwardly extending portion 8 of the usual transmitter 7 into which 90 is screwed any usual construction of mouth-piece 9.

The herein-before mentioned receiving means of the telephone-instrument consists, essentially, of a pair of suitably-shaped tubular arms, as 22 and 23, said arms carrying upon their outer end-portions 24, suitable receivers 25, in communication with the hollow portions of said arms, and electrically connected with the circuit-wires 26, leading 100 into and through said arms, as at 27. Re-

ferring now more particularly to Figure 3 of the drawings, it will be seen that the said arms 22 and 23 are suitably curved, as at 28 and 29, said curved portions being provided with hubs or bearing-portions 30 and 31. Upon their inner flat faces 32, the said hubs or bearing-portions are made with radially extending depressions or grooves, as 33. Extending from the hub 30 of the arm 22 is an arc or other suitably shaped member 34, terminating at its free end in a flat end portion 35, and similarly extending from the hub 31 of the arm 23 is an arc or other suitably shaped member 36, terminating at its free end in a flat end-portion 37, located so as to be placed directly beneath the flat end-portion 35, as shown in said Figure 3, and for the purposes to be presently more fully set forth. Suitably disposed in the hub 30 is a stem 38 having a collar 39 provided with a rib 40, adapted to be brought into retaining engagement with either of the depressions or grooves of said hub. Extending from said collar 39 is an angularly bent shank 41 which is screw-threaded, as at 42, and has a non-threaded shank-portion 43, provided with a stud 44. At its opposite end, the stem 38 has extending therefrom a screw-threaded stem-portion 45, upon which is an adjusting nut 46 and a coil-spring 47. In like manner, there is suitably disposed in the hub 31, a stem 48 having a collar 49 provided with a rib 50 which is adapted to be brought into retaining engagement with either of the depressions of the said hub. Extending from said collar 49 is an angularly bent shank 51, which is screw-threaded, as at 52, and has a non-threaded shank-portion 53, provided with a screw-threaded socket 54, into which the stud 44 extends, as shown in said Figure 3 of the drawings. At its opposite end, the stem 48 has extending therefrom a screw-threaded stem-portion 55, upon which is an adjusting nut 56 and a coil-spring 57. Lock-nuts 58 and 59 are screwed upon the screw-threaded portions 42 and 52, so as to properly maintain fixed relations of the shank-ports 43 and 53 in the members 5 and 6 of the standards or post 1, and also in the tubular portion 8 of the transmitter 7. Suitably connected with the outer end portions 24 of the arms 22 and 23, and having communication with the interior of said tubular arms, are suitably constructed receivers 25.

The manner of raising either one or both of said arms 22 and 23 for hearing purposes will be fully understood from an inspection of Figures 1, 2 and 3 of the drawings, the raised arm or arms remaining in raised position, with the receiver or receivers against the ear or ears of the user of the telephone, without necessitating any further use of the

hands for holding the device against the ear, as with the usual style of telephone. Thus, while talking and listening, the operator has the free use of the hands for other purposes without interrupting conversation over the telephone. When the arms 22 and 23 are lowered, the element 3 is moved in a downward direction, so as to shut off the electric current, as will be evident.

If desired, the contact making and breaking element 4, see Figure 9, may be provided with a hook, as 68, against which the lowered arm is adapted to be moved so as to depress the element 4, and thereby shut off the electric current.

Of course, it will be understood, that any other suitable style and construction of contact-making and breaking means may be employed.

From an inspection of Figure 3 it will be seen, that when the arm 22 is raised, the portion 35 moves out of contact with the portion 37, thus enabling this arm to be used for bearing purposes, with the arm 23 remaining in its lowered and inactive position, thus permitting the use of but one receiver. However, when it is desired to use both receivers, then the arm 23 is raised, the movement of the portion 37 against the portion 35, also causing the arm 22 to be raised into the desired position.

I am also aware, that other changes may be made in the general arrangements and combinations of the various devices and parts, as well as in the details of the construction of the said parts without departing from the scope of the present invention as set forth in the foregoing specification, and as defined in the clauses of the claims, which are appended thereto. Hence, I do not limit my present invention to the exact arrangements and combinations of the various devices and parts, as described in the foregoing specification, nor do I confine myself to the exact details of the construction of the said parts as illustrated in the accompanying drawings.

I claim:

1. A telephone-instrument comprising a standard having perforated ears, said standard being further provided with a make and break control, laterally extending rods mounted in said perforated ears, means upon said rods for preventing displacement of the same from said ears, a transmitter pivotally mounted upon portions of said rods, collars upon said rods, an arm pivotally mounted upon each rod against the collar thereon, a spring and adjusting nut upon each rod for maintaining the relative positions of the arms against said collars, each arm being provided with a rearwardly extending member, a receiver carried by each arm, and means associated with the members of said

arms; whereby movement of one arm and its member will produce a movement of the other arm and its member, one of said arms cooperating with said make and break control.

2. A telephone-instrument comprising a standard having perforated ears, said standard being further provided with a make and break control, laterally extending rods
10 mounted in said perforated ears, means upon said rods for preventing displacement of the same from said ears, a transmitter pivotally mounted upon portions of said rods, collars upon said rods, an arm pivotally mounted upon each rod against the collar thereon, a spring and adjusting nut upon each rod for maintaining the relative positions of the arms against said collars, a receiver carried by each arm, each arm
15 being further provided with a rearwardly extending member, said members being provided with flat end-portions normally in contacting relation with each other, whereby the movement of one arm and its member
20 will produce a movement of the other arm and its member, one of said arms cooperating with said make and break control.
25

3. A telephone-instrument comprising a standard having perforated ears, said standard being further provided with a make and break control, rods mounted in said perforated ears, said rods having portions extending laterally on opposite sides of said ears, one of said rods upon its rearwardly extending portion being provided with a screw-threaded socket, and the other rod being provided upon its inwardly extending portion with a screw-threaded stud screwed into said screw-threaded socket, a transmitter pivotally mounted upon said connected end-portions of the rods, means upon the outwardly extending portions of the rods for preventing displacement of the rods from said ears, collars upon said rods, an arm pivotally mounted upon each rod against the collar thereon, a spring and adjusting nut upon each rod for maintaining the relative positions of the arms against said collars, and a receiver carried by each arm, one of said arms cooperating with said make and break control.

4. A telephone-instrument comprising a standard having perforated ears, said standard being further provided with a make and break control, rods mounted in said perforated ears, said rods having portions extending laterally on opposite sides of said ears, one of said rods upon its inwardly extending portion being provided with a screw-threaded socket, and the other rod being provided upon its inwardly extending portion with a screw-threaded stud screwed into said screw-threaded socket, a transmitter pivotally

mounted upon said connected end-portions 65 of the rods, means upon the outwardly extending portions of the rods for preventing displacement of the rods from said ears, collars upon said rods, an arm pivotally mounted upon each rod against the collar thereon, a spring and adjusting nut upon each rod for maintaining the relative positions of the arms against said collars, a receiver carried by each arm, and means associated with said arms, whereby movement of one arm will produce a movement of the other arm, one of said arms cooperating 70 with said make and break control. 75

5. A telephone-instrument comprising a standard having perforated ears, said standard being further provided with a make and break control, rods mounted in said perforated ears, said rods having portions extending laterally on opposite sides of said ears, one of said rods upon its inwardly extending portion being provided with a screw-threaded socket, and the other rod being provided upon its inwardly extending portion with a screw-threaded stud screwed into said screw-threaded socket, a transmitter pivotally mounted upon said connected end-portions of the rods, means upon the outwardly extending portions of the rods for preventing displacement of the rods from said ears, collars upon said rods, an arm pivotally mounted upon each rod against the collar thereon, a spring and adjusting nut upon each rod for maintaining the relative positions of the arms against said collars, each arm being provided with a rearwardly extending member, a receiver carried by each arm, and means associated with the members of said arms, whereby movement of one arm and its member will produce a movement of the other arm and its member, one of said arms cooperating with said make and break control.

6. A telephone-instrument comprising a standard having perforated ears, said standard being further provided with a make and break control, rods mounted in said perforated ears, said rods having portions extending laterally on opposite sides of said ears, one of said rods upon its inwardly extending portion being provided with a screw-threaded socket, and the other rod being provided upon its inwardly extending portion with a screw-threaded stud screwed into said screw-threaded socket, a transmitter pivotally mounted upon said connected end-110 portions of the rods, means upon the outwardly extending portions of the rods for preventing displacement of the rods from said ears, collars upon said rods, an arm pivotally mounted upon each rod against the collar thereon, a spring and adjusting nut upon each rod for maintaining the relative positions of the arms against said collars, a 115 120 125

receiver carried by each arm, each arm being further provided with a rearwardly extending member, said members being provided with flat end-portions normally in contacting relation with each other, whereby the movement of one arm and its member will produce a movement of the other arm and its

member, one of said arms cooperating with said make and break control.

In testimony, that I claim the invention set forth above I have hereunto set my hand this 17th day of August 1925.

JOHN J. RADEL.
